UNITED STATES PATENT OFFICE.

MARCUS O. ANTHONY, OF NEW YORK, N. Y., ASSIGNOR TO CONTINENTAL ENGINEERING CORPORATION, OF OMAHA, NEBRASKA, A CORPORATION.

VALVE-ROTATING MECHANISM.

Application filed June 23, 1920. Serial No. 391,206.

This invention relates to certain new and useful improvements in the general art of gas engines and is more specifically directed to a rotator adapted for use in connection with the valve mechanisms therefor.

It has been previously attempted, on a number of occasions, to provide a rotating mechanism adapted for use in connection with poppet valves of a gas engine, but 10 these have generally been held defective owing to their complicated natures or else an objectional click present therein during their operation. It is highly essential that structures of this character be simple, durable 15 and efficient and one that will actuate in a noiseless manner.

It is therefore the aim of the present invention to overcome all of these disadvantages by providing a structure of an extremely simple nature and one that is entirely free from the objectionable click.

It is a further object of the invention to provide a rotator which is adapted to rotate the valve during its seating stroke. The advantage gained here will be clearly obvious to those skilled in the art, in that the rotation of the valve during its seating action results in a slight wiping of the seat, thereby removing from the face of the valve, or 30 the seat, the carbonaceous deposits which usually form thereon. This destructive agent, if not removed and allowed to accumulate on the parts mentioned, will result in the pitting of the valve face or its seat 35 which ultimately interferes with the proper functioning of the engine.

Another object of the invention resides in the provision of a rotating mechanism which may be very easily and readily adapted to 40 the standard form of poppet valve now used whether the same be the inlet or the exhaust valve of the engine.

These and other objects will readily present themselves to those skilled in this art 45 upon reading the following specification, in connection with the attached drawings, in which I have merely shown the preferred embodiment of my invention, but it will of course be understood that specific variations 50 therefrom may be resorted to without departing from the spirit of the invention.

Referring to the drawings wherein simi-

lar letters of reference indicate like parts throughout the several views;—

Figure 1 is a fragmentary view taken in 55 section through a portion of the internal combustion engine and showing the valve rotating mechanism in elevation applied thereto.

Figure 2 is an enlarged transverse section 60 through the actuating mechanism for accomplishing the rotative motion to the valve stem.

Figure 3 is a side elevation of a member 65 that is affixed to the valve stem.

Figure 4 is a plan view of the affixed member shown in Fig. 3.

Figure 5 is a plan view of the locking ring 70 for frictionally locking the cap in applied position over the affixed member.

Figure 6 is a side elevation of the actuating means for accomplishing the intermittent motion to the rotating mechanism.

Figure 7 is a front elevation of the structure shown in Figure 6.

Figure 8 is a plan view of the ring member.

Figure 9 is a side elevation of the ring shown in Fig. 8.

Figure 10 is a plan view of the cap member.

Figure 11 is a sectional view of the cap shown in Fig. 10.

In the drawings, 1 indicates a cylinder of an explosive engine, 2 the valve casing attached thereto, 3 a valve seat and 4 the inlet valve stem having a valve head 5 at the end thereof. The valve stem is surrounded by an expansible spring 6 which is held under the state of compression against the usual cross 85 key 7 extending through the lower end of the valve stem 4. All of the parts so far described are of the usual standard construction and no claim thereto is made in this application. It is to this general type of 90 valve that the present improvement is adapted to be attached.

The essential structures embodied in the present case involves what I term a clutch mechanism which, in its assembled relation, 100 is attached to the lower portion of the valve stem 4, and an actuator for said clutch member comprising a yoked member stationarily held in position against the under face of the

valve casing of the engine. This actuator cooperates with the clutch mechanism so as to impart a rotary impulse to the valve stem during the seating stroke of the valve.

- 5 In dealing with the clutch mechanism shown, it will be noted that the member designated 8 is provided with a central bore 9 for the reception of the valve stem 4, and the under face of this member is notched as at 10—10, for receiving the cross key 7 on the valve stem 4. The member 8 has a central upstanding body portion indicated at 11, the upper surface of which is grooved as at 12 forming one wall of a ball raceway. 10
- 15 A toothed member designated 13 is provided on its under face with pins 14, and this toothed member is arranged to snugly fit the upstanding body portion 11 of the member 8 and is held from rotation thereon when the 20 pins are inserted in openings 15 in the member 8. While I have described and shown this toothed member as being a separate element of the structure it may be, and preferably is, made as an integral part thereof. 25
- 25 On the body portion 11, slightly above the member 13, is a groove 16, the purpose of which will be hereinafter referred to. Corresponding in height to the teeth of the member 13 and slightly spaced from the peripheral edges thereof is a ring 17. This ring is rotatably supported on the member 8 and coacts with the toothed member 13 to form a clutch through the interpositioning of balls 18. This ring is also provided with diamet- 30
- 35 rically outstanding lugs 19 for a purpose hereinafter described. In order that these parts, so far described, might be held in an assembled relation to permit of their attachment or removal as an entirety to or from the valve, I provide a locking cap designated 20. This cap has a peripheral flange against which the lower end of the expansible spring 6 bears, and is also provided with a central recess designated 22 which is adapted to fit 40
- 45 over the upper end of the upstanding body portion 11 on the member 8. A ball raceway 23 is also provided within the recess 22, between which and the groove 12 in the upper surface of the upstanding body portion of the member 8 bearings 24 are placed. Arranged within the recess of this cap there is positioned a locking ring 25 which, when the cap is placed over the parts of the clutch, snaps into the groove 16, thereby locking the 50 entire mechanism in an assembled relation, in which condition it may, as a unit, be attached to or removed from the valve stem. 55
- The actuating means, whereby the clutch mechanism may be given the necessary rotary impulses, consists of a yoke-shaped member, the head portion 26 of which has a central opening therein to permit the passage of the valve stem and depending from opposite sides of the head portion 26 are 60 arms 27—27. These arms 27—27 have en-

larged terminal portions indicated at 28 which are slotted as shown at 29—29. This actuator, when in position, is adapted to be held in its place of anchorage within a circular undercut portion on the valve casing 70 by the upper end of the expansible spring 6 engaging the inner face of the head portion 26. Also, if desired, the head portion 26 may be notched as at 30 to receive a pin 31 integrally secured to the valve casing. This 75 prevents relative rotary movement between the actuator and the casing which is likely to happen during the constant vibrations of the engine while in operation. The arms 27—27 depend externally of the sides of the 80 spring 6 and are of a sufficient length so that the lugs 19—19 on the clutch mechanism will at all times be positioned within the slots 29—29. In applying this rotator to any 85 standard type of valve, such as described, all that is necessary to do is to remove the expansible spring from the valve stem to permit the insertion of the actuator, replace the spring and insert beneath the same the clutch unit, this latter being held in operative relation on the valve stem by the interlock afforded through the use of the cross key. During the operation of the engine the valve 90 will be intermittently unseated through the usual tappet mechanism and through this movement the lugs 19—19 on the ring member 17 slide upwardly within the slots 29—29 in the actuator. The ring simply idles during this unseating movement, but on the down or seating stroke the action of the ball clutch within the parts is such as to interlock the ring with the member 8 affixed to the valve stem which results in a positive 95 rotary impulse to the valve. This rotary impulse is such as to continue while the valve is seating and results in a wiping action between the valve head and its seat, thereby removing any carbonaceous deposits which may be therebetween. 100

What I claim is:—

1. The combination with a poppet valve, its seat and spring, a rotator for said valve comprising a flanged body affixed to the valve and having therein a peripheral toothed member, a ring surrounding the toothed member, a ball clutch between said ring and the toothed body, a cap having a rotative interlocking engagement with the flanged body for holding the peripheral toothed member, the ring and the ball clutch in assembled relation, and means for actuating the ring during the operation of said valve. 115
2. The combination with a poppet valve, its seat and spring, a rotator for said valve comprising a member affixed to the same and having thereon a peripheral toothed body, an oscillatory ring supported on the member around the toothed body, a ball clutch between said ring and the toothed body, a 120
- 130

spring and a cap having interlocking engagement with the affixed member for holding the parts in assembled relation, said cap forming a bearing against which the lower 5 end of the spring rests, and means for oscillating the ring during the operation of the valve.

3. In combination with a poppet valve, its seat and spring, a rotating mechanism for 10 said valve comprising a clutch associated with the valve stem adjacent the end thereof and against which one end of the spring bears, and a yoke shaped member against which opposite end of the spring bears arranged 15 exteriorly of the spring and cooperating at its lower end with the clutch for actuating the latter during the operation of the valve.

4. In combination with a valve, its seat and spring, a rotating mechanism for said 20 valve comprising a flanged body affixed to the valve stem, an oscillatory member associated with said flanged body and having between the same and the body a ball clutch, said oscillatory member provided with lugs 25 projecting beyond the sides of the flanged body, a cap superimposed over the upper end of the flanged body, and rotatively interlocking therewith, and means operatively associated with the lugs on the oscillatory mem- 30 ber for actuating the same during the operations of the valve.

5. The combination with a poppet valve, its seat and spring, a rotary mechanism for said valve, comprising a member affixed to the valve stem and having associated therewith a series of teeth, a ring surrounding the teeth and having interposed therebetween a series of balls, a cap loosely mounted on the valve stem and against which the lower end of the spring bears, said cap having means 40 for an interlocking engagement with the affixed member, and means for actuating the ring during the operations of the valve.

6. The combination with a poppet valve, its seat and spring, a rotator for said valve 45 comprising a member affixed to the valve stem and having a central upstanding body portion with a peripheral toothed member thereabout, a loosely mounted cap on the valve stem rotatably engaged with said 50 body portion and having a flange corresponding in area to the base of the affixed member, an oscillatory band interposed between the flange of the cap and the base of the affixed member, a series of balls arranged between 55 said band and the toothed member, and means for actuating the band during the operation of the valve.

In testimony whereof I hereunto affix my signature.

MARCUS O. ANTHONY.
